UNITED STATES PATENT OFFICE.

GIOVANNI DE MEO, OF GENOA, ITALY.

PROPELLING SYSTEM FOR SHIPS.

Application filed June 16, 1925. Serial No. 37,571.

To all whom it may concern:

Be it known that I, GIOVANNI DE MEO, a subject of the King of Italy, residing at 31 Via XX Settembre, Genoa, Italy, have 5 invented certain new and useful Improvements in Propelling Systems for Ships, of which the following is a specification.

This invention relates to the propulsion of ships and vessels and has for its object to 10 provide means to overcome the vibration incidental to the use of screw propellers and the conventional arrangement of the driving mechanism therefor.

Experience has shown that the modern 15 tendency of building longer and longer ships and vessels, results in the use of excessively long propeller shafting and also increases the changes of the propellers and their shafts racing, due to the pitching of the vessel.

20 From careful experiments made by the inventor it has been shown that vibration is due at least to two causes: (1) The excessive length of the propeller shafting with the motive power at one end and the screw propeller 25 at the other behind or adjacent the stern, and (2) that the water passes to and through the propeller blades at an angle to the shaft axis instead of flowing parallel thereto.

According to the present invention, the 30 vibrational effects in a ship are overcome by arranging the propelling means on each side of the vessel at or about midship and driven by a motor arranged as close as possible thereto, each propeller being housed 35 in a recess of stream line form and situated just above the bilge portion of the keel, and with the axis of the propeller shaft situated inside the line or surface of the hull, whereby the water flowing to and through the 40 blades will move parallel with the longitudinal axis of the propeller shaft.

In connection with screw propellers for ships, it has been proposed in order to divide the engine power to arrange the engines and 45 propellers in pairs on opposite sides of the hull, each engine directly driving its own propeller shaft. Each propeller is accommodated in a longitudinal depression of the hull but the form of such depression is not 50 such as would decrease the resistance to the flow of water and moreover the arrangement of the motor entails an excrescence on the hull that will still further increase the resistance.

55 It has also been suggested in a small boat to arrange a propeller amidship, the shaft thereof forming a part of a crank shaft, and

the arrangement being housed within a recess of partly annular form beneath each side of the hull.

There will now be described with reference to the accompanying drawings one embodiment by way of the example for carrying the invention into effect.

Figure 1 shows, diagrammatically, side view of a vessel driven by steam engines of 65 the reciprocating type or by steam turbines in driving connection with the propelling system according to the present invention.

Figure 2 shows diagrammatically in plan view the propeller applied to a vessel. 70

Figure 3 shows diagrammatically in transverse view the recess at each side of the ship, in which the propellers are arranged.

Figures 4 and 5 are diagrammatic transverse sections of the ship taken on the lines 75 X—X and Y—Y respectively, of Figure 2.

Figure 6 represents, diagrammatically, and in larger scale, the horizontal section of the recess A through the propeller shaft with the horizontal projection of the new 80 propelling system.

Figure 7 shows in larger scale the transverse position of the screw propeller and its connection with the propeller shaft.

Figure 8 shows diagrammatically and on 85 an enlarged scale the propeller with one blade in section composed of four consecutive blades forming in total an helicoidal propelling surface.

Figures 9, 10, 11 and 12 show, each in 90 end view and cross section, some details of the bosses of propeller blades for different sizes or cases.

Towards the lower part of the sides of a ship and beneath the water load line, in the 95 corresponding region of the centre of gravity of displacement or center of buoyancy of the vessel, in normal loaded draft and at a sufficient depth of water above the edges of the propeller blades, is a recess A of determined and sufficient size and form, as shown in Figures 2 and 6, where the propelling system is arranged. The line of the recess and its form alongside the hull is of such geometrical form and extension as to ensure that the total skin friction or frictional resistance of the submerged part of the hull is not increased as compared with a hull of ordinary construction. The recess is given a practical 100 shape in accordance with the changing form of the geometrical transverse section in order to give free passage to the stream of water

- arising from the combined motion of the submerged hull and of the present propelling system, the determination of the proper or suitable shape being calculated for each type of vessel and for a determined speed of normal running of the ship, say by calculation or by experiments in a Froude tank.
- In each of the recesses A, above mentioned, is installed the propeller shaft B parallel or not to the longitudinal section of the hull and situated at such height to avoid any emersion of the propeller blades even at the maximum angle of rolling of the ships in normal condition of sea-going. The propeller shaft B is connected with the motor shaft of the propelling machinery through a stern bushing C and to the thrust bearing S (Figure 2) and to the reduction gears D connected to the turbines F or other type of propulsion engines. The opposite end of the propeller shaft is supported by a suitable bracket H and protecting terminal cone N. Between the stern bushing C and the bracket H are installed, properly keyed, the consecutive propeller blades, each with its own boss L. The bosses L are properly connected with the keys G in such position that the propeller blades I are disposed circumferentially at equal distance between, forming a total circumference. The propeller bosses are to be fixed with proper screw nuts M or by other suitable stops to fix in proper position the various blades to the propeller shaft.
- The propeller blades I are disposed symmetrically, following an entirely helicoidal surface of one complete pitch, adapting the propelling system for any reasonable number of propeller blades from three and more.
- The use of propellers in which the blades are arranged on the shaft one behind the other is not generally new and no broad claim is made herein to such a form.
- The propeller blades I may be cast in one with their bosses in case of small engine power, or can be keyed, as shown in Figures 7, 8, 9 and 10, or by other systems in use, or adapted, within limits, for suitable adjustments of their pitch. In both cases the most suitable pitch of the propeller blades, for a determined form or size and propelling power, can be obtained by calculation or by experience in order to obtain the best propelling efficiency.
- The above illustrated new propelling system, disposed alongside the vessel, and the practical impossibility that all the propeller blades can emerge above the water line during changes in the running condition of the ship in heavy seas, due to pitching and rolling, show clearly how the system contributes to the almost entire elimination of the vibrations mainly caused by the normal and extraordinary reactions arising from

the present practice of propelling at the stern and, consequently, how far stability can be obtained, even transverse, on modern ships.

Obviously for the proper practical application of the above illustrated device the adjacent water lines of the hull can be suitably modified; the propelling machinery can be disposed differently than in use at present, but the great economical and commercial advantages arising from the application of this new system of ship propulsion, even for some classes of vessels already built and others to be built, will render convenient the general practical adoption of the above device, even for better protection of screw propellers in some special class of war vessels or in recently built both passenger and mercantile ships.

Constructional variations of the embodiment fully described above are possible but without departing from the main principles and objects of the present device.

Having now particularly described and ascertained the nature of my said invention and in what manner the same is to be performed, I declare that what I claim is:

1. Improved propelling system for the purpose of overcoming vibration in a ship or vessel, comprising propelling means arranged on each side of the vessel at or about midship, a motor to drive said propelling means arranged in close proximity thereto, each propeller being housed and arranged entirely in a recess of streamline form with which the ship is provided and situated just above the bilge portion of the keel and so that no portion of the propeller projects beyond the outline of the hull, and with the axis of the propeller shaft situated inside the line or surface of the hull, whereby the water flowing to and through the blades will move parallel with the longitudinal axis of the propeller shaft.

2. The combination with a propelling system as claimed in claim 1, of screw propellers comprising a series of propeller blades, each with its own boss successively keyed one behind the other and radially displaced on the longitudinal horizontal propeller shaft at such a distance, both circumferential and longitudinal, that the propelling blade surfaces are substantially on the same cylindrical helicoidal surface, forming together a whole pitch of the screw propeller, the propeller shaft being supported at one end by a suitable bracket and at the other end by an adapted stern tube reaching inside a suitable thrust block and ending in the reduction gear connected to the turbines or other system of propelling machinery.

In witness whereof I affix my signature.

GIOVANNI DE MEO.
